(57) **CLAIM**

The ornamental design for a hanging chair, as shown and described.

DESCRIPTION

FIG. 1 is a perspective view thereof;

FIG. 2 is a perspective view of the hanging chair shown in an environment of use;

FIG. 3 is a front elevational view of FIG. 1;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines shown in the figures depict environmental structure that form no part of the claimed design.
